United States Patent Office

Des. 183,885
Patented Nov. 11, 1958

183,885

MAGNIFIER

Edward J. Herbert, Scarsdale, N. Y.

Application November 4, 1957, Serial No. 48,320

Term of patent 14 years

(Cl. D57—1)

Fig. 1 is a front elevation of a magnifier embodying my new design; and

Fig. 2 is an edge view of the magnifier.

The rear face of the magnifier is the same as the front face.

I claim:

The ornamental design for a magnifier, as shown and described.
